Mower Patented Nov. 2, 1858.

UNITED STATES PATENT OFFICE.

C. T. STETSON, OF AMHERST, MASSACHUSETTS.

IMPROVEMENT IN HARVESTERS.

Specification forming part of Letters Patent No. 21,993, dated November 2, 1858.

To all whom it may concern:

Be it known that I, CHARLES T. STETSON, of Amherst, in the county of Hampshire and State of Massachusetts, have invented sundry new and useful Improvements in Harvesting-Machines; and I do hereby declare that the following is a full and exact description thereof, reference being had to the accompanying drawings, making a part of this specification.

Figure 1 is a top view of my improved harvesting-machine; Fig. 2, a side elevation of the same; Fig. 3, a section in the line $x-x$ of Fig. 1; Fig. 4, a section in the line $y-y$ of Fig. 1; Fig. 5, a section in the line $z-z$ of Fig. 2; Fig. 6, a top view of a full-sized improved cutter combined with a finger and a section of a finger-bar; Fig. 7, a side view of the same, and Fig. 8 a section in the line $z'-z'$ of Fig. 6.

Similar letters indicate like parts in each drawing.

The rectangular frame of my improved harvesting-machine is composed of the timbers A C D E F G, which are arranged and combined with each other as represented in the drawings. One side of the said frame is supported by the driving-wheel I, which is located in a central position between the timbers E D, and the opposite side of said frame is supported by the smaller wheels t t', which are pivoted between the prongs of the vertical shanks n n'. The said shanks n n' pass freely through apertures in the side beam, C, and the upper ends of the same are made fast to the adjustable beam B. The beam B is connected at each end to the beam C by means of the screws p p', which rise from the latter beam and pass through apertures in the former, where they are made fast by means of a pair of screw-nuts upon each of said screws, the one above and the other below the said beam B. This manner of supporting the frame of the machine enables its inner side to be elevated or depressed at pleasure, and it also enables either end of said frame to be elevated or depressed for the purpose of giving the proper inclination to the fingers c c and the finger-bar a.

The cutting apparatus of my improved harvester is constructed in such a manner as to produce an oblique drawing cut between the moving and the stationary cutting-edges. This is accomplished by combining two double-edged tapering cutters, b' b', with a single shank, b,

and then forming the fulcrum-pivot hole of said cutter in a central position in the forward end of its shank b preparatory to jointing the same to every other finger in the finger-bar.

It will therefore be perceived that the innermost edges of my improved oscillating cutters act in conjunction with the two edges of the fingers to which the said cutters are pivoted, while the outermost edges of said cutters act in conjunction with the cutting-edges of the intermediate fingers.

A steel cutter-plate, o, is combined with each finger to act in conjunction with my improved oscillating cutters. Another advantage resulting from this my improved method of constructing the cutting apparatus of a harvester is that the number of joints is reduced one-half when compared with any other arrangement of pivoted cutters, which necessarily produces a diminution of friction at the same time that it greatly diminishes the liability to accidents.

The fingers c c are combined with the finger-bar a in any suitable manner. The after end of each cutter-shank b is jointed to the reciprocating bar e, which is operated in the manner represented in the drawings. At its inner end the finger-bar a is jointed to the vertically-sliding head j by means of the pivot s. The sliding head j plays freely between the guiding-cheeks k k, which descend from the under side of the beam C. The lower end of the said sliding head j is bolted to the central portion of a stiff plate, whose perforated ends l l incline upward and loosely embrace the shanks of the screws m m, which project from the under side of the beam C, and thereby form self-adjusting fore and aft braces to the said sliding head. The joint-pivot q of the angular lever g passes through the sliding head j, and is embraced by the guiding-blocks r r, which play loosely in vertical slots in the cheeks k k. The angular lever g is connected to the lower end of the reciprocating cutter-bar e by means of the short pitman i, and the upper end of said lever is connected with the propelling-crank H by means of the pitman f. Motion is imparted to the crank-shaft by means of a toothed wheel on the shaft of the driving-wheel I gearing into a toothed wheel on the shaft J, and by a toothed wheel on the latter shaft gearing into a toothed wheel on the crank-shaft.

An upwardly-curving stiff arm, a', is securely fastened to the inner end of the finger-bar a,

and the extremity of said arm plays loosely between the guiding-cheeks *d d*, which are secured to the side of the beam *A*. The said curved arm *a'* prevents an injurious degree of straining action from being exerted upon the pivot *s* or upon the cheeks *k k*, which guide the sliding head *j* of the cutter-bar in its movements, and consequently the effect of the said arm *a'* and its guiding-cheeks *d d* will be to cause both ends of the said cutter-bar to freely vibrate up and down to such an extent as will enable said cutter-bar to adapt itself to the varying surface of the mowing or harvest field.

Having thus fully described my improved harvesting-machine, what I claim therein as new, and desire to secure by Letters Patent, is—

1. Combining two double-edged cutting-blades with each of the vibrating cutter-shanks

for the purpose of reducing the number of joints in the cutting apparatus, substantially as herein set forth.

2. Combining an inwardly-extending curved arm, *a'*, with the inner end of the finger-bar, when the vibrating end of said arm is made to play between guiding-cheeks or in a guiding-groove, and the said inner end of the finger-bar is jointed to a vertically-sliding head, all substantially in the manner and for the purpose herein set forth.

The above specification of my improvements in harvesting-machines signed and witnessed this 19th day of April, 1858.

CHARLES T. STETSON.
